(74) Attorney, Agent, or Firm — Lewis Roca Rothgerber
Christie LLP(57) CLAIM

The ornamental design for a lighting fixture, as shown and described.

DESCRIPTION

FIG. 1 is a perspective view of the new design;
 FIG. 2 is a top view of the design of FIG. 1;
 FIG. 3 is a side view of the design of FIG. 1;
 FIG. 4 is a bottom view of the design of FIG. 1;
 FIG. 5 is a front view of the design of FIG. 1; and,
 FIG. 6 is a rear view of the design of FIG. 1.
 The broken lines shown on the drawings depict portions of the lighting fixture that form no part of the claimed design.
